Filed Jan. 29, 1971, Ser. No. 111,174

Term of patent 14 years

Int. Cl. D24—04, 99

U.S. Cl. D83—1

FIG. 1 is a top plan view of a first embodiment of a compartmentized medicine tray for rest homes, showing my new design;

FIG. 2 is a side elevational view thereof;

FIG. 3 is an end elevational view thereof;

FIG. 4 is an enlarged fragmentary sectional view taken on line 4-4 of FIG. 2, showing surface contours;

FIG. 5 is an enlarged fragmentary perspective view showing a tray region at the intersection of four compartments; and

FIG. 6 is a top plan view of a modified embodiment of the tray illustrated in FIG. 1.

Except for a difference in the number of compartments, the bottom of each embodiment, the tray is unornamented and plane.

I claim:

The ornamental design for a compartmentized medicine tray for rest homes, substantially as shown and described.
